UNITED STATES PATENT OFFICE.

BLANCHE E. LEAVITT, OF CHICAGO, ILLINOIS.

BRASSIÈRE.

1,294,492.

Specification of Letters Patent. Patented Feb. 18, 1919.

Application filed July 15, 1918. Serial No. 244,876.

To all whom it may concern:

Be it known that I, BLANCHE E. LEAVITT, a citizen of the United States, residing at Chicago, in the county of Cook and State of Illinois, have invented certain new and useful Improvements in Brassières, of which the following is a specification.

This invention relates more particularly to brassières or garments or devices which are adapted to support the figure of the wearer, and to confine the bust and diaphragm particularly of a fleshy person, to graceful outlines.

The objects of this invention are to produce a brassière which is so constructed that it will serve as a support in an unusually satisfactory and efficient manner; to provide a device of the character indicated, which is comparatively simple in construction and may be readily applied by the wearer; to provide a device or support having a relatively wide range of adjustment, while at the same time being exceedingly flexible and comfortable; and in general to provide such an improved device or garment as will be described more fully hereinafter. In the accompanying drawings illustrating a preferred form of my invention:

Figure 1 is a side view of the device shown in position on the wearer;

Fig. 2 is a view of the body portion shown in extended position;

Fig. 3 is a front view of the device shown in position on the wearer; and,

Fig. 4 is a rear view of the device shown in position on the wearer.

My improved brassière may be said in general to consist of a novel bust or body portion with straps provided for the device for holding the same in position. As shown in the drawings, the body portion 5 comprises a rear or back section 6 and side or front sections 7 and 8. The front sections are connected to the back section by means of elastic bands or connections 9, and lacing 10. The bands 9 are positioned at the lower edges of sections, while the lacing extends upwardly and permits a certain amount of flexibility between the sections as well as affording means for adjustment. The several sections are preferably provided with stays 11 in the positions indicated. The rear section 6 is preferably made uniform throughout and is formed of suitable fabric so as to readily adjust itself closely to the wearer.

The front sections preferably comprise lower band or belt-like portions 12 which are comparatively unyielding, and upper body portions 13 which are more or less yielding. Darts 14 are preferably made in the upper edges of the front portions to make them conform more closely to the figure. The bands or lower sections 12 may be conveniently made of cloth cut with the grain so that it will not readily stretch.

The meeting edges of the front sections 7 and 8 are preferably substantially straight at the top and then curve outwardly, as indicated at 15, so that the lower portions 16 will be sufficiently long to overlap, as indicated particularly in Fig. 3. The upper portions of these edges are provided with any suitable fastening devices such as hooks and eyes 16. Straps or bands 17 and 18 are secured to the narrow overlapping ends of the belt portions 12. These straps are of sufficient length to pass partially around the body of the wearer, and then down to points adjacent to the knees where the free ends 19 are fastened preferably by means of fasteners 19 which connect them to the stockings. The lower ends of the straps are preferably formed of elastic 20, or if desired, the entire straps may be formed of such elastic material. Loops 21 and 22 are fastened to the front pieces 7 and 8 at the sides, and serve to guide and fasten the straps 17 and 18.

The brassière may be provided with shoulder straps 23, the ends of which are secured by detachable fasteners 24 so that the straps may be omitted if desired.

When the garment is to be worn, it is applied in the usual manner, and the side laces 10 are adjusted so that it will fit the form snugly, and will confine and mold excess flesh so as to give the bust and figure a pleasing appearance. The straps 17 and 18 are then passed around the back to the sides and down through the loops 21 and 22 respectively, and are drawn tight so as to confine the diaphragm the desired amount. The ends, being passed through the loops, tend to hold the overlapping straps and belt portions in position and when the ends of the straps are fastened to the stockings, the bands will be held securely in position and furthermore, the front of the brassière is drawn down so as to give the desired appearance of a "straight front." From the above description it will be seen that I provide a garment or device which is exceed-

ingly novel in construction and which will be particularly efficient in securing the desired result. This device is especially adapted for giving a pleasing appearance to the wearer, and is particularly effective when worn by stout or fleshy persons. It will be noted that changes may be made in the details of construction and arrangement of parts without departing from the scope of the invention, but what I claim and desire to secure by Letters Patent is:

1. A brassière and diaphragm supporter comprising a back portion and front portions adjustably connected therewith, the upper parts of the front portions being arranged to encompass the body of the wearer and having means for fastening the adjacent edges, the lower parts of the front portions being extended to overlap, said overlapping parts having straps adapted to pass around the body and extend downwardly to be secured at points below the waist of the wearer and guide loops at the sides for engagement with said straps.
2. A brassière comprising a back portion and front portions, resilient means for connecting the lower edges of the front portions with the back portion at the waist line only to permit expansion of the diaphragm for breathing, lacing connecting the proximate edges of the back portion and the front portions, said front portions comprising upper and lower parts, said upper parts being of proper length to encompass the bust of the wearer, fastening means for fastening the front edges of the upper parts, said lower parts being extended beyond the upper parts and adapted to overlap, bands secured to the free ends of the lower parts, loops secured to the lower edges of the front portions, said bands being adapted to pass around the back of the wearer and down through the loops

on the opposite side, and having means at the ends thereof for securing them to the stockings.

3. An article of clothing comprising a wide belt-like member adapted to encircle the bust of the wearer, the front lower portions thereof being extended to overlap and being provided with straps or bands, fastening devices at the sides of said member, and catches at the ends of said straps, the arrangement being such that said straps may be passed around the back of the wearer and through the fastening devices on the opposite sides to adjust the device, and the catches may then be secured to the garments on either side of the person at some point below the waist in order to draw the lower portion of the device closely around the body and to draw the entire device downwardly.

4. A brassière comprising a plurality of adjustably connected sections, the upper portion being of suitable length to encircle the body of the wearer, fastening devices for the front edges of the upper portion, the lower portions being extended to overlap, loops at the sides thereof, said extensions having straps which are adapted to be passed around the back of the wearer and through the opposite loops and secured at some distance below the lower edge of the device for holding the same in proper position.

5. A brassière comprising a plurality of adjustably connected sections, loops secured to the sides and positioned somewhat toward the front, straps projecting from the lower edges of the front portions and having fasteners at the ends thereof, said straps being adapted to pass around the back of the wearer and through the loops on the opposite sides with the fasteners engaged to the stockings.

BLANCHE E. LEAVITT.
